UNITED STATES PATENT OFFICE.

JAMES F. DINN, OF PORT WASHINGTON, NEW YORK, ASSIGNOR TO HALL-BORCHIERT DRESS FORM COMPANY, OF NEW YORK, N. Y., A CORPORATION OF NEW JERSEY.

DRESS-FORM.

1,167,388.

Specification of Letters Patent.

Patented Jan. 11, 1916.

Application filed July 3, 1914. Serial No. 848,882.

To all whom it may concern:

Be it known that I, JAMES F. DINN, a citizen of the United States, residing at Port Washington, county of Nassau, State 5 of New York, have invented an Improvement in Dress-Forms, of which the following description, in connection with the accompanying drawing, is a specification, like characters on the drawing representing like parts.

This invention relates to dress forms and particularly to dress forms of that nature wherein the body portion of the form is expanded or contracted by turning the central 15 supporting rod relative to the body. In dress forms of this nature any turning movement of the form body relative to the supporting rod will cause the dress form to expand or contract and thus change the circumference 20 measure of the form at the waist. In using dress forms of this nature it is desirable that the form should be capable of turning on the supporting pedestal in order that when a dress is draped thereon 25 the dressmaker may turn the form so as to bring different portions of the dress into view, and it is also desirable to be able to effect this relative turning movement between the form and pedestal without danger 30 that the form will be turned relative to the central supporting rod and thereby have its correct adjustment disturbed.

It is the object of my invention to provide a novel supporting means for a dress form 35 of this nature whereby the form can be freely turned about its pedestal without changing the adjustment of the size of the form in any particular, and I accomplish this end by providing a novel swivel connection 40 between the central supporting rod and the supporting standard or pedestal which permits the rod to turn while at the same time clamping it in its vertically-adjusted position.

In order to give a proper understanding 45 of my invention I have illustrated herein a selected embodiment thereof which will now be described after which the novel features will be pointed out in the appended claim.

Referring to the drawings, Figure 1 is a 50 front view of a dress form embodying my invention with portions broken out to better show the mechanism for adjusting the form; Fig. 2 is an enlarged vertical section

through my improved swivel clamping device for the vertical supporting rod.

I have shown at 1 the body portion of a dress form which is made up of a plurality of sections adjustable relative to each other as usual in adjustable dress forms. This 60 body portion is sustained on a central supporting rod 2 which in turn is adjustably secured to a supporting standard or pedestal 30 as usual in dress forms, the latter being provided with the foot or base portion 65 40 and the tubular standard 50 into which the rod 2 telescopes.

One type of dress form which is known commercially is constructed so that the size of the waist of the form can be adjusted by 70 a relative turning movement between the form body 1 and the central supporting rod 2. One way of accomplishing this is providing the rod 2 with the right and left screw-threaded portions 3 and 4 on which 75 are screw-threaded the two collars 5 and 6 that are connected to the sections of the form by the struts or braces 7 and 8 so that when the rod 2 is turned in either direction relative to the form body 1 the collars 5 and 80 6 will be moved toward or from each other thereby to expand or contract the form. I have also shown for expanding the neck of the form a sleeve 9 loosely mounted on the rod 2 and having screw-threaded engagement 85 with two collars 10 and 11 that are connected to the neck sections by means of struts or braces 12 so that when the sleeve 9 is turned on the rod by means of the hand-wheel 13 the neck will be expanded or contracted.

In order to preserve any adjustment of the waist of the form after it has once been made, it is essential that the form should not be rotated relative to the central-supporting rod 2, for if this is done such rotation will move the collars 5 and 6 toward or from each other thereby expanding or contracting the form. In the use of dress forms it is also desirable to be able to turn 100 the form around while a dress is draped thereon so as to permit the dressmaker to see different sides of the form, but if the central supporting rod 2 is fixedly clamped in the pedestal 30, such turning of the form 105 body will, of course, change the size of the waist.

In order to provide a construction which

permits the form to be freely turned about the pedestal without changing its size I have provided the novel construction which is shown best in Fig. 2 and which embodies a 5 swivel connection between the clamp for the 10 rod 2 and the pedestal. As herein illustrated the part 50 of the standard is provided at its upper end with a head or rod-supporting member 14 which is swiveled to 15 the part 50 and through which the rod 2 extends, said rod being clamped to the head in any suitable way as by means of a clamping screw 15. Because of the swivel connection between this head and the pedestal 20 it is possible to turn the form about the pedestal without giving any relative turning movement between the body of the form and the supporting rod 2.

The swivel connection between the head 25 20 and the portion 50 of the standard may be provided for in any suitable way, but will preferably be such as to form a permanent connection between these parts. As herein shown the tubular member 50 has a cap member 16 screw-threaded to its upper end, 30 said cap member being provided at its upper end with a central opening surrounded by an inturned flange 17 and the head 14 is provided with a neck portion 18 adapted to enter said aperture. This head portion is 35 preferably made of malleable metal so that the lower edge 19 of the neck 18 can be bent outwardly to underlie the flange 17, thus permanently connecting the parts. Either 40 the underside of the head 14 or the top of the cap member 16 or both are provided with ball races in which anti-friction balls 20 are received whereby an anti-friction ball bearing is provided between the head 14 and the cap member 16. By this construction

the head 14 is permanently united to the standard 30, but is freely rotatable thereabout. When the dress form is to be raised or lowered the set screw 15 can be loosened, thus permitting the rod 2 to be adjusted to any desired height. After the set screw 15 is tightened the form and the rod 2 may be freely turned relative to the standard 30 without effecting any change in the adjusted size of the form.

It is sometimes desirable to lock the vertical rod 2 from rotation, and this may be accomplished by providing a set screw 21 which is located in the cap part 16 and is adapted to engage the rod 2.

My invention is capable of being applied to any dress form, and while I have illustrated herein a selected embodiment of my invention I do not wish to be limited to the constructional details shown.

I claim:

In a dress form, the combination with a tubular supporting member provided at its upper end with an inwardly-directed annular flange, of a clamping member having a neck extending through said flange, the end of the neck being enlarged to underlie the flange whereby the clamping member is swiveled to the tubular supporting member, a dress form body having a central supporting rod extending through the clamping member, and means to clamp said member adjustably to said rod.

In testimony whereof, I have signed my name to this specification, in the presence of two subscribing witnesses.

JAMES F. DINN.
